UNITED STATES PATENT OFFICE

WILLIS K. HODGMAN, JR., OF TAUNTON, MASSACHUSETTS

DRY PIPE VALVE

Application filed June 29, 1927. Serial No. 202,435.

This invention relates to dry pipe valves and has for its general object to improve dry pipe valves in the particulars hereinafter set forth.

5 In a dry pipe valve embodying my invention the water valve and the air valve are independently pivoted on opposite sides of the waterway and when the valves are closed the air valve bears directly on the 10 water valve, the said water valve being loosely connected to its supporting arm in such a way that no part of the pressure of the air valve is taken by the arm, the entire pressure of the air valve coming directly on 15 the water valve.

A further feature of the invention relates to a novel form of latch for holding the water valve open.

The drawing illustrates a sectional view 20 through the dry pipe valve embodying my invention.

The valve herein shown comprises a casing 1 having an inlet 2 and an outlet 2', said inlet and outlet being connected by a water-way as usual in dry pipe valves. This 25 waterway is adapted to be closed by both a water valve 3 and an air valve 4, the water valve being adapted to seat on a valve seat 5 at the end of the inlet 2 and the air valve 30 having the usual flexible peripheral flange 6 which is adapted to seat on an air valve seat 7 which is shown as set obliquely across the waterway.

The air valve 4 is carried by an arm 8 35 which is pivotally mounted in the casing at 9 so that the valve may swing from closed to open position as shown by full and dotted lines in the drawing.

The water valve 3 is carried by another 40 arm 10 which is pivotally mounted at 11 on the opposite side of the waterway so that when the dry pipe valve trips the water valve and air valve swing in opposite directions and take positions on opposite sides of 45 the waterway as shown by dotted lines.

The casing 1 is provided with the usual neutral chamber 20 between the water valve and air valve and which is provided with a drain port 28 adapted to be closed by a drip valve 24 that is normally held open so long as the water valve is closed but which is closed when the water valve opens all as usual in dry pipe valves.

One feature of the present invention relates to a construction by which when the valves are closed the air valve 4 bears directly on the water valve 3, the entire pressure on the air valve being transmitted to the water valve and none of the pressure being transmitted or taken by the arm 10 or its pivot 11. To accomplish this end the water valve 3 is provided with a stem 12 which extends loosely through an opening 13 in the horizontal portion 14 of the arm 10, the opening 13 preferably being appreciably larger than the stem 12 so that the latter may have a certain amount of movement in the aperture. The stem 12 projects above the horizontal portion 14 of the arm 10 and the air valve 4 is provided at its under face with an extension 15 which rests directly on the upper end of the stem. Said stem 12 is provided with a pin 16 which is situated above the arm 10 and prevents the water valve from becoming detached from the arm.

With this arrangement when the valves are closed the air valve bears directly on the stem 12 of the water valve and the entire pressure on the air valve is thus taken by the water valve, none of said pressure being transmitted to the arm 10 or to its pivot bearing 11 because of the loose fit between the stem 12 and the arm 10. This loose fit is not only in a lateral direction but also in a vertical direction since there is more or less play between the pin 16 and the top of the horizontal portion 14 of the arm 10. The water valve 3 is thus loosely connected to the arm 10 in such a way as to permit a limited

free relative movement between the valve and the arm 10 in any direction lateral to the axis of the valve as well as in a direction in the line of said axis. With this construction the pressure on the air valve is transmitted directly to the water valve independently of the arm 10, the function of the latter being principally to guide the water valve in its opening movement. An advantage resulting from this structure is that the water valve will always be properly seated even though the bearings for the arm 10 may not be perfectly aligned and, therefore, less precision is required in the mounting of the arm 10 than would be the case if the water valve were fixedly carried by the arm or if the pressure of the air valve was transmitted to the water valve through the arm.

Another feature of the invention relates to the construction involved in latching the water valve in open position. The arm 10 has a locking latch 29 pivotally mounted thereon, said latch being carried by a rock shaft 17 which is journaled in the arm, said rock shaft having a weight 18 fast thereon. This latch is adapted to co-operate with an abutment 19 which is rigid with the casing 1 and projects into the neutral chamber 20.

When the water valve is closed the latch is retained in full line position by the weight 18, said latch at this time resting against the stop 21 which is carried by the arm 10. As the water valve swings into open position the nose 22 of the latch strikes the corner 23 of the abutment and as the valve completes its opening movement the latch will be turned anti-clockwise by its engagement with the abutment until the arm 10 has been carried to a position where the latch will wipe under the abutment. As soon as this position has been reached the weight 18 will swing the latch into its operative position shown in dotted lines thus bringing the nose 22 thereof beneath the under face of the abutment, the latch at this time resting against the stop 21. When in this position the latch will by its engagement with the abutment prevent the water valve from closing as will be obvious.

The neutral chamber 20 is provided with the usual drip valve 24 which is held open so long as the water valve and air valve are closed but which is automatically closed when the water valve opens. This drip valve is shown as connected to an arm 25 pivotally mounted on the pivot pin 11 and said arm has an upstanding finger 26 adapted to engage a lug 27 extending from the arm 10. These parts are so arranged that when the water valve is closed the engagement of the finger 26 with the lug 27 will hold the drip valve open but as soon as the water valve opens the drip valve is allowed to close.

I claim:

1. In a dry pipe valve, a casing having a

waterway, a pivotally-mounted air valve adapted to close the waterway, a water valve also adapted to close the waterway, said air valve and water valve being provided with co-operating portions which directly engage each other when the valves are closed, and a swinging arm pivotally mounted in the casing and loosely connected to the water valve to permit limited free movement between the valve and the arm in any direction transverse to the axis of the valve, the pressure on the air valve being transmitted directly to the water valve independently of said arm through said co-operating portions, and said arm functioning merely as a means to guide the water valve in its opening movement, which is in a direction different from that of the air valve.

2. In a dry pipe valve, a casing having a waterway, a pivotally-mounted air valve adapted to close the waterway, a water valve also adapted to close the waterway and provided with an upstanding stem, said air valve having a portion which directly engages said stem when the valves are closed, a swinging arm pivoted to the casing and provided with an opening larger than said stem and through which the latter extends, and means to prevent the stem from being withdrawn from the aperture, the pressure on the air valve being transmitted directly to the water valve through said stem independently of the arm and the latter functioning merely as a means to guide the water valve in its opening movement, which is in a direction different from that of the air valve.

3. In a dry pipe valve, a casing having a waterway, a water valve adapted to close said waterway, a pivoted arm by which the water valve is carried, an air valve constructed to bear directly on the water valve when the valves are closed, a weighted latch pivoted to said arm, and an abutment carried by the casing and so situated that when the water valve is moved into open position the latch will engage the abutment and by reason of its pivotal mounting will turn against the influence of its weight to a position where it will pass under the abutment, the weighted portion of the latch then automatically swinging it into operative position in which it co-operates with the abutment to lock the water valve open.

4. In a dry pipe valve, a casing having a waterway, a pivotally-mounted air valve adapted to close the waterway, a water valve also adapted to close the waterway, said air valve and water valve being provided with co-operating portions which directly engage each other when the valves are closed, a swinging arm which is separate from the water valve and is pivotally mounted in the casing and is loosely connected to the water valve to permit limited free movement between the valve and arm in directions both

transverse and parallel to the axis of the valve, the pressure on the air valve being transmitted directly to the water valve independently of said arm through said co-operating portions, and said arm functioning merely as a means to guide the water valve in its opening movement which is in a direction different from that of the air valve.

In testimony whereof, I have signed my
10 name to this specification.
